UNITED STATES PATENT OFFICE.

HARRY H. HAZELTINE, OF TACOMA, WASHINGTON.

DESIGN FOR A PNEUMATIC TIRE.

52,822.

Specification for Design.

Patented Dec. 31, 1918.

Application filed March 11, 1918. Serial No. 221,859. Term of patent 14 years.

To all whom it may concern:

Be it known that I, HARRY H. HAZELTINE, a citizen of the United States, residing at Tacoma, in the county of Pierce and State of Washington, have invented a new, original, and ornamental Design for Pneumatic Tires, of which the following is a specification, reference being had to the accompanying drawing, forming a part thereof.

Figure 1 is a plan view of a fragment of

a pneumatic tire showing my design. Fig. 2 is a sectional view of same.

I claim:

The ornamental design for a pneumatic tire as shown.

HARRY H. HAZELTINE.

Witnesses:

FRANK H. FOWLER,
WINIFRED KNOPH.
